Primary Examiner — Karen S Acker

(74) Attorney, Agent, or Firm — IPUSA, PLLC

(57) **CLAIM**

The ornamental design for a seat belt material, as shown and described.

DESCRIPTION

FIG. 1 is a front view of a seat belt material, showing our new design; and,

FIG. 2 is a rear view, thereof.

The right, left, top and bottom views of the seat belt material of FIG. 1 have been omitted because they form no part of the claimed design.
